Des. 223,845

Patented June 13, 1972

223,845

POKER GAME BOARD

Theodore Lane Roberson, 8 Hillcrest Road, Box 619,
Ogden Dunes, Portage, Ind. 46368

Continuation-in-part of design application Ser. No. 21,237,
Feb. 3, 1970. This application Jan. 29, 1971, Ser.
No. 111,172

Term of patent 14 years

Int. Cl. D21—01

U.S. Cl. D34—5

Fig. 1

Fig. 2

FIG. 1 is a plan view of the poker game board of my design; and

FIG. 2 is a poker game board shown partially folded showing the edge and back side thereof.

This is a continuation-in-part of design application Ser. No. D-21,237, filed Feb. 3, 1970, now abandoned.

I claim:

The ornamental design for a poker game board, substantially as shown and described.
